CLAIM

(21) Appl. No.: **29/131,819**

We claim the ornamental design for clamp bracket assembly with J-shaped linkage arms for use with push button latch and lock operating assemblies, as shown and described.

(22) Filed: **Oct. 27, 2000**

DESCRIPTION

Related U.S. Application Data

(63) Continuation-in-part of application No. 29/113,063, filed on Oct. 28, 1999.

Reference is made to utility application Ser. No. 09/698,416 filed (concurrently herewith) by Lee S. Weinerman et al entitled Push Button Operators for Latches and Locks, and Locking Systems Employing Lockable Push Button Operators, which discloses a lock system that may employ a clamp bracket assembly with J-shaped linkage arms of the type disclosed herein.

(51) LOC (7) Cl. **08-07**

FIG. 1 is a perspective view showing principally top and front portions of a clamp bracket assembly with J-shaped linkage arms for use with push button latch and lock operating assemblies embodying our new design;

(52) U.S. Cl. **D8/330**; D8/343

FIG. 2 is a perspective view showing principally bottom and rear portions thereof;

(58) Field of Search D8/330, 331, 336, D8/343; 292/83, 208, 210, 216, 209, 300, 309, 63, 56; 285/312

FIG. 3 is a front view thereof;

(56) **References Cited**

FIG. 4 is a rear view thereof;

U.S. PATENT DOCUMENTS

FIG. 5 is a right side view thereof, it being understood that the left side view is a mirror image reversal of the right side view;

FIG. 6 is a top view thereof;

(List continued on next page.)

FIG. 7 is a bottom view thereof;

OTHER PUBLICATIONS

FIG. 8 is a perspective view similar to FIG. 1 but showing the J-shaped arms thereof pivoted; and,

Eberhard Manufacturing Co, Cleveland, OH "Industrial, Vehicular & Specialty Hardware—Catalog 107," 1996, Cover & pp. 63–69.

FIG. 9 is a perspective view identical to FIG. 1 but with a push button latch and lock operating assembly depicted in broken lines.

Tri/Mark, New Hampton, IA "40–400 Push Button Center Control" 2-page brochure, Dated Jan. 1998.

The broken line disclosure of a push button latch and lock operating assembly in FIG. 9 is for illustrative purposes only and forms no part of the design.
